UNITED STATES PATENT OFFICE.

JOHN WALDHEIM, OF ELIZABETH, NEW JERSEY, ASSIGNOR TO UNDERWOOD TYPEWRITER COMPANY, OF NEW YORK, N. Y., A CORPORATION OF DELAWARE.

TYPEWRITING MACHINE.

Application filed May 4, 1925. Serial No. 27,744.

This invention relates to improvements in packs which are fitted tightly upon the frames of typewriting machines for reducing the sound of operation.

5 Usually a pack comprises a base, side walls and a rear wall, all lined with sound-deadening cushions or material upon which the sound waves are caught and by which they are absorbed, the floor and walls forming an 10 air-pocket which promotes the absorption of the sound. Said walls usually terminate below the carriage of the typewriting machine, which overhangs the machine-frame and travels considerably beyond the sides of said 15 frame.

An object of the invention is to improve the pack, with a view to effecting a further substantial reduction in the noise of operation of the machine, while preserving the advantage of the pack, and while facilitating the operation of the machine and making it unnecessary to alter its construction.

To these and other ends, the pack is built up with a carriage-enclosing chamber, which 25 permits the use of an ordinary carriage having the ordinary appurtenances, and which constantly exposes the work to view while rendering it feasible to insert and manipulate the work-sheet, and to manipulate the carriage in all ways. The carriage-chamber comprises a floor-portion, which 30 consists of felt-covered shelves extending outwardly from the top of the pack, and which also comprises end walls, a rear wall 35 and a top wall, the latter overlying said shelves, and said walls forming a carriage-chamber which is a substantial element in reducing the noise, but which is open at the front for the insertion of the operator's 40 hand to manipulate the carriage and the work-sheets. The side walls, rear wall and top wall of said cover are not fixed, but are hinged to swing back and off from the pack, leaving the carriage fully exposed for various 45 manipulations. The cover carries at its front a glass, so that the cover may overhang the typewriter-carriage to the front thereof, thus conducting to an efficient air-pocketing. The various parts of the pocketing 50 co-operate with the remaining parts thereof to reflect the sound from wall to wall, and to absorb it, so that very little escapes at the front of the machine, even

though said front is open for the manipulation of the carriage.

The sides of the cover are in the form of plates or ears which extend downwardly, overlapping the side walls of the pack and hinged at their lower ends to said side walls, preferably at approximately the center of gravity of the cover for ease in manipulating the same; the cover being held by its own weight in either closed or open position.

The rear wall of the pack may be divided into two portions, one of which is fixed on the pack and extends up therefrom, and the other of which forms a portion of said cover and swings therewith; said portions joining to make a single wall.

Another feature of the invention is that 70 the air-pocket is extended to form a work-sheet pocket at the back of the machine in rear of said pack; the rear wall of the pocket being extended up and joining the rear wall of the hinged cover, as aforesaid.

The improved typewriting machine pack is simply designed and inexpensive, and is highly efficient as a device for subduing noise.

Another feature of this invention relates 80 to the provision of means whereby the marginal stops are exposed, so as to be manually operable from the outside of the casing. To this end, there is provided a front plate having a felt lining fast thereto, and the felt 85 lining extends upwardly under the marginal stops, so that the stops are slid able in the usual manner, while at the same time preventing the passage of sound waves through the opening under the marginal stops.

There is provided a window to render the work-sheet visible at the printing point. In my prior application No. 733,286, filed August 21, 1924, there is provided an opening at the front of the casing to both operate the 95 machine and to render the printing point visible. In order to render the printing point visible, however, it has been necessary to make the opening larger than necessary to operate the machine and consequently permit the escapement of more sound waves and generally reduce the sound-deadening efficiency of the casing. By providing a glass panel at the front edge of the cover it is possible to reduce considerably the width 100 of the opening through which the carriage is

operated, while still maintaining the visibility of the work-sheet in the casing.

In sound-deadening casings having a front opening it has been found that it considerably increases the efficiency of the cabinet to have the sound-absorbing walls as near as possible to the noise-producing parts. The quicker the sound waves are absorbed the less chance they have to find their way to the outside through the opening in front of the casing. In this invention the lower walls under the carriage forming the carriage-extensions at the sides of the pack form a convex closure closely fitting the carriage of the machine, a feature considerably increasing the efficiency of the casing.

In one form the present invention provides for the adapting of the casing to machines having a tabulating device. Said device includes a tabulating stop at the rear of the machine frame, and to this end the rear wall of the pack is provided with an opening to clear the stops.

Other features and advantages will hereinafter appear.

In the accompanying drawings,

Figure 1 is a cross-sectional view in elevation of the sound-deadening casing enclosing an Underwood standard typewriting machine.

Figure 2 is a front view in elevation, showing the margin stop devices of the machine and the front plate attached to the casing.

Figure 3 is a perspective view of the casing with the machine removed therefrom.

Figure 4 is a side view in elevation of the sound-deadening casing, showing the machine therein and the cover swung back to its open position.

Figure 5 is a dismembered perspective view of the sound-deadening casing.

Figure 6 is a perspective view of the body-part of the casing, showing a modification arranged to receive a typewriting machine having tabulating keys.

The Underwood standard typewriting machine comprises a main frame 10 supported by feet 11, and has a forward extension 12 carrying banks of keys 13 to cause type-bars to strike a platen 14 when the keys are depressed. The platen is revolubly mounted upon a carriage 15 mounted for letter-feed movement upon rails borne by the frame of the machine.

Machines of this general character are noisy in operation, and it is for the purpose of deadening the noise arising from the operation thereof that this sound-deadening casing is provided.

The sound-deadening casing comprises broadly a lower pack 16, a cover or canopy 17 and a front closure 18 fast to the frame of the machine. Forming an integral part of the pack 16 and at the rear thereof there is

provided a pocket 19 to accommodate the overhanging unused portion of a work-sheet 20. The pack is designed to closely fit the frame of the machine, and comprises a rear wall 21, two side walls 22 and a bottom wall 23 or sole 23. In line with the rear wall 21 and extending therefrom there are provided walls 24 forming the continuous front wall of the pocket 19 at the rear of the pack. From said front wall, extending rearwardly, and forming an integral part thereof, there are provided end walls 25 which are joined together at the rear thereof by a rear wall 26 for completely enclosing the pocket. The bottom wall or floor 27 of the pocket forms a continuous surface with the sole of the pack, as shown in Figure 1. Both the pack and the pocket are lined with a layer of sound-deadening material, such as felt, and is generally indicated in the drawings by the numeral 28. The function of the felt lining in the pack is to absorb the sound waves emanating from the operation of the machine, and to present a yielding surface to the frame of the machine to thus effectively hold the machine in the pack. The felt lining 28 upon the wall 26 of the pocket extends upwardly from said wall as shown in Figure 5, in which the extension is indicated by the numeral 30. To facilitate the insertion of the work-sheet around the platen, and to prevent the leading edge 29 of the work-sheet from being obstructed by the upper edge of the felt lining, the latter is beveled at 31.

The cover 17 is pivotally mounted upon screws 32 fast to the end walls 25 of the pocket 19. The fulcrum point of the cover is so placed upon side walls 32 that the cover will be held by its own weight either in its closed position or in its open position shown in Figure 4. In order to limit the travel of the cover, there is provided a pin 33 fast to one of the end walls 25 engaging with a circular slot 34 in one of the side walls of the cover. The two side walls 32 are joined together by a curved top 35 forming an integral part of said side walls. The top 35 slopes downwardly toward the front thereof, and at the rear is bent downwardly and terminates with a vertically disposed rear wall 36 overlapping the upstanding portion 30 of the felt lining 28.

In order to render the machine operable from the outside of the casing, especially for such operations as the returning and positioning of the carriage and the line-spacing of the platen, without necessitating the displacement of the cover at each operation, there is provided an opening or slot in front of the casing extending the full width of the casing, through which opening the hand may be thrust to reach the carriage-controlling levers, and then the hand is slid along the slot to move the carriage. Sound-

deadening casings have been provided with an opening at the front thereof wide enough to render the work-sheet visible and to render the machine operable. In this kind of casing much more of the casing than was strictly necessary to render the machine operable had to be left open in order to render the printing point visible. In this invention an effort has been made to reduce the size of the opening, and to this end there is provided a glass plate 37 fastened to the top of the cover by means of clamping pieces 38 and screws 39. Said glass plate over-extends the side walls of the cover and is provided with a ground edge 40 to prevent injury to the hand when the same is moved along the opening to return the carriage. In this manner it is possible to reduce the size of the slot or opening in front of the casing to just the amount required to operate the machine, the visibility of the work-sheet being obtained through the glass plate.

In accordance with one of the features of this invention the lower walls 41 of the carriage pockets are designed to closely fit the outline of the carriage to thus absorb the sound waves emanating from the operation of the machine as near as possible to their source. Said lower walls form an integral part of the pack and extend outwardly from the side walls thereof. Referring more particularly to Figure 5, it will be noted that the walls 41 extend rearwardly, forming a convex curvature 42, and terminate with flat portions 43 in line with the top edge of the end walls 25 of the pocket 19. It will also be noted that front edges 44 of the walls 41 are provided with folded ribs 45 to control and hold the edge of the felt lining 28 which covers said walls.

The cover 17 is lined with a layer 47 of sound-deadening material. Said lining is glued or otherwise secured to the walls of the cover and extends downwardly overlapping the sides of the casing to seal the joint between the two members. The side walls 32 of the cover are bent outwardly at 48 to make room for the felt lining 47. In order to facilitate the opening and closing of the cover, there is provided an angular piece 49 fast to one of the sides of the cover by means of fasteners 50.

In the Underwood machine there are provided marginal stops 51 slidably mounted upon a rod 52 in front of the machine. Said stops are operable from the outside of the machine by means of handles 53, and in this manner the stops may be positioned to control the length of the lines upon the work-sheet. In this invention an effort has been made to retain the advantage of easily adjusting the marginal stops while at the same time sealing the opening under the stops and thus prevent the leakage of sound waves therethrough. To this end there is

provided a plate 54 attachable to the frame of the machine by means of screws 55 fitting into tapped holes in the frame. The plate is lined with a piece of felt 56 over-extending the plate at the top thereof. Said extension, indicated by the numeral 57, is curved inwardly under the stops as shown in Figure 1. The upper edge 58 of the felt extension 57 is designed to normally bear under the stop carrying rod 52 but when the stops are moved the edge 58 yields to permit the passage of the stops and then springs back to its normal position as shown in Figure 2.

In order that the plate may be fastened to or removed from the machine without necessitating the previous removing of the ribbon control keys 59, while at the same time retaining the advantage of being able to operate the keys from the outside of the casing, there is provided a slot 60, said slot having an enlargement 61 which serves as a clearance for the key-travel-limiting pin 62 fast to the key-lever 63.

In order that the sound-deadening casing 90 may accommodate typewriting machines having a tabulating mechanism including tabulating stops at the rear of the machine frame, a modification of the present invention is illustrated in Figure 6, in which the 95 rear wall of the pack 16 is provided with an opening 64 to clear the tabulating mechanism. Otherwise, the construction of the pack illustrated in Figure 6 is the same as the pack 16 and consequently the designating numerals are identical in both packs.

It will be noted, among other things, that the hood or canopy is provided across the front thereof with a hand-opening, through which the usual standard machine carriage 105 controls may be manipulated, and any standard machine may be set into the sound-deadening casing without special elongated carriage-controlling levers; that the glassed-in cover overhangs the front of 110 the canopy and has no front glass-enclosing rail to obstruct the vision of the operator; and that the front plate that bridges the sound-deadening machine-enclosure at the front thereof has a pliable sound-absorbing 115 longitudinal edge to engage the machine-frame, and becomes self-adjusting to any inequalities in the frame and to any variations in the height of the margin-stop devices from the rubber feet in different machines.

Variations may be resorted to within the scope of the invention, and portions of the improvements may be used without others.

Having thus described my invention, I 125 claim:

1. A sound-deadening casing for a type-writing machine including a body-part, a hood and a front plate, the body-part including rear and side walls forming a three-

- sided machine-enclosure closely fitting the frame of the machine, and carriage-receiving enclosures at each side of the machine-enclosure, the hood being swingably mounted upon the body-part to cover and uncover the machine-enclosures, and the front plate being detachably secured to the front wall of the machine to bridge the machine-enclosure.
5. A sound-deadening casing for a typewriting machine having a carriage and carriage-controlling mechanisms, said casing including a machine-pocket to enclose the frame of the machine on three sides, a carriage-receiving pocket at each side of the machine-enclosing pocket, and a hood swingable over the casing to cover all the pockets, said hood when closed forming a longitudinal hand-opening through which the usual carriage-controls may be manipulated at any position of the carriage.
10. 2. A sound-deadening casing for a typewriting machine having a carriage arranged for letter-space travel and having marginal stops in front of said carriage to limit the longitudinal travel thereof, of a sound-deadening casing comprising a body-part, a cover pivotally mounted on said body-part, the cover having an opening at the front through which the carriage may be manipulated, and a front closure having a felt lining fast thereto and overextending the top thereof, said extension serving as means to seal the opening under the marginal stops.
15. 3. The combination with a typewriting machine having a carriage arranged for letter-space travel and having marginal stops in front of said carriage to limit the longitudinal travel thereof, of a sound-deadening casing comprising a body-part, a cover pivotally mounted on said body-part, the cover having an opening at the front through which the carriage may be manipulated, and a front closure having a felt lining fast thereto and overextending the top thereof, said extension serving as means to seal the opening under the marginal stops.
20. 4. The combination with a typewriting machine having a carriage arranged for letter-space travel and having marginal stops in front of said carriage to limit the longitudinal travel thereof, of a sound-deadening casing comprising a body-part, a cover pivotally mounted on said body-part, the cover having an opening at the front through which the carriage may be manipulated, and a front closure having a felt lining fast thereto and overextending the top thereof, said extension serving as means to seal the opening under the marginal stops, the cover being provided with a glass plate fast thereto and in the line of vision of the operative, through which glass plate a work-sheet is rendered visible without displacement of the cover.
25. 5. The combination with a typewriting machine having a carriage arranged for letter-space travel and having marginal stops in front of said carriage to limit the longitudinal travel thereof, of a sound-deadening casing comprising a body-part, a cover pivotally mounted on said body-part, the cover having an opening at the front through which the carriage may be manipulated, and a front closure having a felt lining fast thereto and overextending the top thereof, said extension serving as means to seal the opening under the marginal stops, the front closure being fast to the frame of the machine independently of either the body-part or the cover and bodily removable with the machine.
30. 6. The combination with a typewriting machine having a carriage arranged for letter-space travel and having marginal stops in front of said carriage to limit the longitudinal travel thereof, of a sound-deadening casing comprising a body-part, a cover pivotally mounted on said body-part, the cover having an opening at the front through which the carriage may be manipulated, and a front closure having a felt lining fast thereto and overextending the top thereof, said extension serving as means to seal the opening under the marginal stops, the front closure being provided with a clearance slot for engagement with the shaft of a ribbon-control-key operatively mounted on the machine-frame, and with means to render the front closure attachable to and removable from the machine-frame.
35. 7. A sound-deadening casing for a typewriting machine having a traveling carriage, said casing including a sound-deadening machine-enclosure to encase three sides of the machine-frame, a sound-deadening insert to partially close up the front of the machine-enclosure, open-ended sound-deadening wings merging with both sides of the machine-enclosure to accommodate the travel of the carriage, and a canopy to cover the casing and close the ends of the wings.
40. 8. A sound-deadening casing for a typewriting machine having a traveling carriage, said casing including a sound-deadening machine-enclosure to encase three sides of the machine-frame, a sound-deadening insert to partially close up the front of the machine-enclosure, open-ended sound-deadening wings merging with both sides of the machine-enclosure to accommodate the travel of the carriage, and a canopy to cover the casing and close the ends of the wings, said canopy having an open front to give access to the carriage.
45. 9. A sound-deadening casing for a typewriting machine having a traveling carriage, said casing including a sound-deadening machine-enclosure to encase three sides of the machine-frame, a sound-deadening insert to partially close up the front of the machine-enclosure, open-ended sound-deadening wings merging with both sides of the machine-enclosure to accommodate the travel of the carriage, and a canopy to cover the casing and close the ends of the wings, said canopy having an open front to give access to the carriage, and a glassed-in top-opening to expose the carriage.
50. 10. A sound-deadening casing for a typewriting machine having a traveling carriage, said casing including a sound-deadening ma-

- chine-enclosure, sound-deadening wings on both sides of the machine-enclosure, a hood to cover the casing, and a sound-deadening insert to encase the front of the machine between the wings, said insert having a pliable edge that is self-adjusting to the frame of the machine.
11. A sound-deadening casing for a type-writing machine having a carriage arranged for letter-space travel and marginal stops adjustably mounted in front of the machine for controlling the length of the lines upon a work-sheet, said casing comprising a pack closely fitting three sides of the frame of the machine, a front closure detachably mounted on the front wall of the machine and having a flexible upper section to abut the marginal stops, lateral extensions integral with the sides of the pack to form carriage-receiving pockets, and a cover straddling the carriage-receiving pockets, said cover having a front opening through which the operation of the carriage may be controlled.
12. A sound-deadening casing for a type-writing machine having a carriage arranged for letter-space travel and marginal stops adjustably mounted in front of the machine for controlling the length of the lines upon a work-sheet, said casing comprising a pack closely fitting three sides of the frame of the machine, a front closure detachably mounted on the front wall of the machine and having a flexible upper section to abut the marginal stops, lateral extensions integral with the sides of the casing to form carriage-receiving pockets, and a cover straddling the carriage-receiving pockets, said cover having a front opening through which the operation of the carriage may be controlled, said cover being also provided with a glass-sealed opening to expose the printing line of the machine.
13. A sound-deadening casing for a type-writing machine having a traveling carriage and means for controlling the carriage, said casing including a sound-deadening enclosure to fit three sides of the machine, a sound-deadening insert to partially close up the front of the machine and expose the keyboard, sound-deadening side wings at both sides of the machine-enclosure to accommodate the travel of the carriage, and a hood having an open front throughout the length thereof to give access to the carriage-con-
- trolling elements at any position of the carriage.
14. A sound-deadening casing for a type-writing machine having a traveling carriage, said casing including a sound-deadening enclosure for the machine, a work-sheet enclosure at the rear of the machine-enclosure co-extensive with the width of the casing, open-ended wings at either side of the machine-enclosure to enclose the under part of the traveling carriage and then merge with the work-sheet enclosure, and a hood to enclose the top of the casing and the open ends of the wings.
15. A sound-deadening casing for a type-writing machine having a traveling carriage, said casing including a sound-deadening pocket to enclose the frame of the machine upon three sides, a sound-deadening carriage-receiving pocket at each side of the machine-pocket, a sound-deadening insert to partially enclose the front of the machine and bridge the gap between the two carriage-receiving pockets, and a sound-absorbing hood mounted to cover and uncover the casing, said hood when closed co-operating with the carriage-receiving pockets and insert to form a longitudinal opening giving access to the carriage.
16. A sound-deadening casing for a type-writing machine having a traveling carriage and carriage-controlling elements, said casing including a T-shaped floor, a central walled-in sound-deadening pocket rising from the floor to enclose the machine, a rear pocket coextensive with the length of the casing formed between the rear wall of the casing and the rear wall of the machine-enclosing pocket, open-ended clearance spaces at each side of the machine-pocket for the traveling carriage, which merge with the rear pocket, and a hood to cover the casing and enclose the ends of said clearance spaces, said hood being open at the front side to give access through the opening for the manipulation of the carriage-controlling elements.
17. A sound-deadening casing for a type-writing machine, said casing including a sound-deadening machine-enclosure, and a canopy to cover said enclosure, said canopy having an open front and a glassed-in top, the front edge of the glass overhanging the open front of the canopy.

JOHN WALDHEIM.
